UNITED STATES PATENT OFFICE.

JOHN W. SMITH, OF ERIE, PENNSYLVANIA, ASSIGNOR TO BALL ENGINE COMPANY, OF ERIE, PENNSYLVANIA, A CORPORATION OF PENNSYLVANIA.

STEAM-TURBINE.

No. 861,909.

Specification of Letters Patent.

Patented July 30, 1907.

Application filed January 12, 1905. Serial No. 240,750.

To all whom it may concern:

Be it known that I, JOHN W. SMITH, a citizen of the United States, residing in Erie, in the county of Erie and State of Pennsylvania, have invented certain new and useful Improvements in Steam-Turbines, of which the following is a specification.

This invention relates generically to steam-turbines of that class in which the steam is caused to expand several times and in which the steam, at each successive stage of expansion, is caused to impinge against the buckets of the turbine-wheel, and so propel the same onwardly; the utilization of the energy resident in the steam being such that when the steam finally exhausts almost all the energy has been transformed into useful work.

The invention relates more particularly to improvements to U. S. Patent No. 777,313, issued December 13, 1904, to which reference is here made.

The invention consists of an improved means of regulating the amount and tension of steam passing through a series of gradually increasing chambers and the there-to pertaining buckets, by which regulation the torque and the speed may be varied without appreciably influencing the efficiency.

The invention consists further of a novel double-bucket to which steam is supplied by an admission-chamber common to the inlet-ends of this double-bucket, and from which, after having passed through the buckets, the steam emanates simultaneously from the two outlet-ends of the double-buckets and enters twin release-chambers, from which the steam passes into the adjacent admission-chamber common to both inlet-ends of the next double-bucket.

The invention consists further of a turbine-wheel provided with curved channels, the walls separating which are provided with cut-out portions, and a division-wall protruding into the cut-out portions, forming buckets with the channels, and relatively stationary to the moving bucket wheel. And the invention consists lastly of certain novel combinations of parts which will be fully described hereinafter and finally pointed out in the claims.

In the accompanying drawings, Figure 1 represents a vertical longitudinal central section of my improved steam-turbine, showing a high, intermediate and low-pressure turbine, and a reversing-turbine, all of these turbines being connected on one common shaft and each being an axial-flow turbine, having double-buckets, admission-chambers common to both inlet-ends of the double-buckets, and twin release-chambers for the outlet-ends of the buckets, Fig. 2 shows a vertical-section of a radial-flow turbine, Fig. 3 is a detail-view of a bucket-construction, Fig. 4 is a detail-view of an axial-flow turbine, showing a twin nozzle for the double-

bucket, Fig. 5 is a detail-view of an axial-flow turbine, 55 showing rotor and stator buckets, Fig. 6 is a detail view of an axial-flow turbine, having rotor and stator buckets and twin release-chambers, Fig. 7 is an end-view of the turbines shown in Fig. 1, Fig. 8 shows a development of the circular portion of the steam-turbine, showing 60 clearly the buckets, the admission-blades, the partitions forming the admission-chambers, partitions forming the release-chambers, and steam-regulating valves, and Fig. 9 shows a horizontal section of Fig. 8, taken on line 9—9 of Fig. 8. 65

Similar letters of reference indicate corresponding parts.

My improved steam-turbine consists of a high, intermediate and low-pressure turbine, and a reversing-turbine, each of which turbines consists of a casing provided with partitions, so as to form a series of high-pressure, intermediate-pressure, low-pressure, and reversing-chambers. The chambers of the first three mentioned turbines are so arranged that the steam, after passing through the high-pressure chambers and buckets, 70 and having there expended considerable of its energy, passes into the intermediate chambers and buckets, and giving up some further part of its energy, passes into the low-pressure chambers and buckets, and there expends its remaining energy, so that when it finally 75 exhausts practically all the available energy originally resident in the steam has been converted to useful work. Each of these series of chambers is composed of intercommunicating admission and release-chambers, which serve to direct the steam to the buckets, 80 receive the steam from the same, and guide the steam from the release-chambers again to an admission-chamber to be again by the same directed against the succeeding buckets, received by the next release-chambers and guided to the next admission-chamber in such 85 a way as to cause the steam to partake of a spiral path from the steam-inlet to the steam-outlet.

Referring to the drawings, and more particularly to Fig. 1, A designates the high-pressure casing, B the intermediate-pressure casing, C the low-pressure casing, and D the casing of the reversing-turbine. These casings are provided with suitable supports E, shown in Fig. 6, and in their central part with openings for the passage of the shaft F on which the turbine-wheels A¹, B¹, C¹ and D¹ are secured. Between the casings 90 A, B and C, diaphragms G¹ and G² are arranged, which are provided at their central part with journal-bearings for the shaft F. These diaphragms form air-spaces between the casings and thereby prevent any heat-transference from one to the other. The turbine-wheels A¹, B¹, C¹ and D¹ are provided at their peripheral parts with a plurality of buckets of U-shape, arranged in pairs, so as to form double U-buckets with

the inlet-ends of the buckets adjacent each other and the outlet-ends of the buckets furthest apart. These buckets H are formed by mortising double U-shaped channels in the wheels and having their inlet-ends of 5 preferably rectangular shape and their outlet-ends somewhat larger than the inlet-ends, the latter feature being of some advantage when the peripheral speed of the moving element is considerably less than one-half of the speed of the impinging jet. This is especially so when two velocity-reductions are made at one 10 expansion, as shown in Fig. 5. The mortised channels at their central portion are rectangular in cross-section with rounded corners, or approximately circular. These channels may be lined with closed tubes 15 of proper shape and held in place by a ring R¹, as shown in Fig. 2, or may be left simply as such. A novel means is shown in Fig. 4, where the space between the wheel and a downwardly-extending portion of a ring R, to be more fully described hereinafter, forms 20 the bucket proper.

To prevent shocks, the cross-sectional area of the channels through which the steam passes should increase at a point where the velocity falls. This area 25 may be increased in different ways. One way, by varying the angle of the bucket-walls; and another, by constructing the buckets with a varying radius.

In order to avail of the energy still resident in the steam, the steam is directed successively into the adjacent buckets until the desired, preferably the entire, 30 energy of the steam has been expended, after which it is exhausted into the condenser. For this purpose the high-pressure, intermediate-pressure and low-pressure casings, and the reversing-pressure casing are each divided into a plurality of admission and release-chambers by partitions. As the intermediate-pressure, 35 low-pressure and reversing turbines are similar in principle to the high-pressure turbine, they will not be separately described in detail. The partitions forming these chambers are so arranged as to form chambers gradually increasing in size in proportion to the 40 expansion of the steam, each stage of which is estimated in relation to a given inlet-pressure and capacity; the size of the chambers being such as to maintain the speed of the steam consistent with obtaining the 45 greatest available amount of work from the same.

Between the lower ends of the partitions M forming the admission-chambers are arranged a plurality of admission-blades N, spaced equally apart, which form nozzles intended to secure an effective entrance-velocity of the steam when entering the buckets. These 50 admission-blades are surrounded at their sides with rings R, which are provided with projections which extend into the mortised channels the walls separating the channels being provided with cut-out portions, so 55 that the space between the turbine-wheel and projection forms the bucket proper.

By providing the nozzles above described with a central partition, as shown in Fig. 4, each nozzle is divided so as to form two nozzles, each of which directs the 60 steam into the inlet-end of the bucket corresponding thereto.

Instead of dividing the single nozzles by a partition, two instead of one ring R may be provided, and admission-blades N arranged between the rings.

In Fig. 5 is shown a modified form of turbine, in

which the stationary element is provided with two buckets, and the rotating element with four buckets, of which the two middle ones have their inlet-ends adjacent each other, while adjacent the outlet-ends of these middle buckets the inlet-ends of the two other 70 buckets are arranged, so that the steam directed by the nozzles enters the middle buckets in two streams, each of which passes successively through the middle rotor buckets, the stator buckets, and the outer rotor buckets, and then into the atmosphere and condenser. The 75 object of using the stator buckets is to make a second reduction of velocity. Fig. 6 shows this system of buckets used in connection with twin release-chambers, the outer-end of the buckets discharging into the same.

In Fig. 3 the admission-blade supporting-rings R are 80 rounded off or beveled at the lower ends, so as to allow the egress of the steam from the buckets.

The release-partitions M¹ may either extend clear down to the moving element, allowing, however, sufficient clearance, or may only extend as far down as 85 rings R², between which and the rings R release-blades would be arranged. These release-blades or the lower ends of the partitions as the case may be, are either straight or somewhat scoop-shaped, with a slight portion straight.

The inner surfaces of the rings R², shown in Figs. 1 and 3, are inclined so that the steam may pass quickly out of the buckets when entering the release-chambers.

The periphery of the turbine-wheel is provided with capillary grooves v, which are intended to reduce leakage of the steam when the same passes through the buckets.

The partitions forming the admission and release-chambers are provided with openings M², by means of which these chambers communicate one with the other 100 in such a manner that the steam passing from one admission-chamber common to both inlet-ends of the double-buckets, into a series of buckets in number proportionate to the ratio of expansion, out of the outlet-ends of the double-buckets into the twin release-chambers, through openings of the partitions into the next admission-chamber, into the succeeding series of buckets, out of the same and through the next release-chambers, openings of the partitions, into the next admission-chamber, and so on, partaking in its course of a 105 spiral path and expanding in the gradually increasing chambers during its passage from one series of buckets to the other.

The admission and release-chambers described are 110 not to be considered as separate chambers as such. The casing forms, so to say, one large chamber through which the steam passes successively into the inlet-ends of the buckets, through the buckets and out of the outlet-ends of the buckets, in a somewhat spiral 115 path, from the inlet-valve to the exhaust-channel. The steam entering the double-buckets passes in two streams, each parallel in direction to the shaft, and expending a part of its energy in work of impulse and reaction, emanates from the buckets parallel with the 120 direction of the going steam, each stream entering a release-chamber of the same shape and size. From these twin release-chambers, each stream simultaneously enters the next admission-chamber, which is 125 common to both of the inlet-openings of the next pair 130

of buckets, where some of the energy resident in the steam is expended in propelling the wheel forwardly. The line of direction of the incoming steam in the bucket and the line of direction of the outgoing steam 5 are parallel and in the same plane with the bucket.

Each of the nozzles formed by the admission-blades R¹ corresponds to one or more buckets, but the steam of a plurality of buckets passes directly into the release-chambers.

10 The intermediate-pressure, low-pressure, and reversing-turbines are similar in operation and construction to the high-pressure turbine, excepting in size. In the case of the reversing-turbine the direction of the buckets relatively to the radius of the reversing-turbine wheel and the direction of the admission-blades are reversed in direction to that of the turbine-wheels of the forward turbines; so that when the steam enters the double-buckets of the reversing-turbine, it causes the shaft of the same to rotate in an opposite direction 15 to that of the other turbines.

The high-pressure casing A is provided with a plurality of piston-valves V¹, V² and V³, in sets of preferably three in number. The cylinder W² of each of these valves is supplied with a pipe W¹⁰ through which 20 the actuating-medium enters in order to move the piston W⁵. The cylinder W² is provided at its side with a supply inlet-port W¹¹ and at its lower end with an opening W⁶. The partitions forming the admission and release-chambers hereinbefore described are here, 25 immediately below valves V¹ and V², provided with horizontal portions N⁵, which are provided with openings W⁸. The piston-rod W⁶, secured at one end to the piston W⁵, is provided with two puppet valves W³ and W⁴, the upper one of which is adapted to close 30 the opening W⁹ of the lower end of the cylinder and the lower one of which is adapted to close the opening W⁸ of the horizontal portion N⁵ of the partition-walls. When the piston W⁵ is in its downward position, valve 35 W³ is free from the lower end of the cylinder, and so permits the free ingress of steam, while valve W⁴ closes the opening W⁸ and prevents steam from passing into the release-chamber immediately below the horizontal portion N⁵.

Referring to Fig. 8, valve V² is shown in its downward position and valves V¹ and V³ are shown in their upward position. Hence, steam enters the admission-chamber in communication with the opening W⁹ of the valve V², and is guided into the buckets by the admission-blades forming the nozzles, but cannot enter the release-chamber, also below the valve V², owing to the closing of the opening W⁸ of the horizontal portion N⁵ by the puppet-valve W⁴. The steam, guided by the nozzles, passes through the buckets and enters the succeeding release-chambers, and from the 45 same passes through the opening W⁸ of the horizontal portion N⁵, and into the next admission-chamber and thereto pertaining nozzles and buckets. So, when valve V¹ is in its downward position, steam can only enter the admission-chamber below it, but cannot enter the release-chamber, also below it, and hence interfere with the operation of either of the valves V² or V³. To guide the piston-rod W⁶ a perforated projection W¹¹ is provided.

The particular arrangement of the valves shown 50 may be modified without departing from the spirit of

my invention. So, also, other forms of valves may be used.

From the gradually increasing chambers it is seen that the nozzle-area increases from stage to stage in proportion to the ratio of expansion the machine is designed to work under. When the turbine is operated under ideal conditions, a certain number of stages are necessary to carry out the proper expansion from a given boiler-pressure to a given vacuum. Supposing the turbine to be designed and constructed with a 75 constant initial and terminal pressure and to give its normal output when valve V² is solely used, then on opening either valve V¹ or V³ and on closing valve V² the output will be either increased or decreased. When opening valve V¹ with the other valves closed, 80 an output above the normal will be attained; inasmuch as a larger amount of steam is admitted, and as this steam is subjected to one stage of expansion less than when using valve V². On the other hand, on closing valves V¹ and V², and on opening valve V³, a 85 smaller quantity of steam is permitted to enter, and the steam must undergo one stage of expansion more than when valve V¹ is used and two stages more than when valve V³ alone is used. The steam in this last named case being subjected to more stages of expansion, the 90 final tension is decreased and the vacuum of the condenser increased, inasmuch as steam of a lower tension enters the same. The effect of this will be to make room for another stage of expansion. Hence, with a slight increase of vacuum, the range of expansion may 95 be increased one whole stage, and on account thereof the turbine operated at a high efficiency at loads below the normal, or at comparatively light loads.

For overload conditions, when using valve V¹, the complete expansion of the steam is not attained, as 100 there is not a sufficient number of stages, and as there is some loss in the form of residual velocity. This residual velocity is not, however, sufficient to constitute an increase in the number of stages of expansion and varies in amount, depending on the design of the turbine. On using valve V¹, the torque and speed of the 105 turbine are greatly increased, accompanied by but a slight lowering of the efficiency, depending, as mentioned, on the residual velocity of the steam. The speed of the steam passing through the buckets is also 110 increased, so that in order to attain the highest efficiency it would be necessary to have the angles of the buckets correspond to the increased angular velocity of the turbine-wheel. Hence, by using valve V² a normal output, speed and torque are obtained, while on 115 using valve V³ the output, torque and speed are decreased, and on using valve V¹ these factors are increased.

To form connection between the high, intermediate and low-pressure casings, pipes P are provided, which 120 connect the last of a series of high-pressure release-chambers with the first of a series of intermediate-pressure admission-chambers and the last of a series of intermediate-pressure release-chambers with the first of a series of low-pressure admission-chambers. Suitable 125 outlet-openings or flanges O are provided to permit the exhaust of the steam, now substantially devoid of energy, into the atmosphere or conduct the same to a suitable condenser. The turbine-wheels of the individual turbines are provided with holes S, which permit the 130

passage of steam from one side of the wheel to the other, so as to prevent any unequal pressure, due to a greater collection of steam on one side than on the other.

It is usual in marine engineering to distribute the power necessary for propelling boats between three propeller-shafts in case of a triple-screw boat. In such a case the high-pressure turbine is connected with the middle propeller-shaft and generates about one-third of the energy, and the low-pressure turbines are connected with each of the remaining shafts. Suitable pipes conduct the steam, after having done its work in the high-pressure turbine, to the low-pressure turbines. When maneuvering, the high-pressure turbine may be put out of action and high-pressure steam admitted directly to the low-pressure turbines, in which case the low-pressure turbines are provided with separate controlling valves, and the various ranges of speed of the side shafts obtained, thus causing one side turbine to run at a greater speed than the other. By 20 providing the low-pressure turbine-shafts each with a reversing-turbine, the latter may be actuated and so its shaft rotated in a reverse direction to that of the other side-shaft.

Suitable piping is connected directly to the main supply-pipe P^0 and high-pressure steam admitted by pipe P^2 to suitable reducing-valves P^3 and P^5 directly to the low-pressure casings or directly to the reversing-turbine casing.

With a slight loss of efficiency due to leakage and 30 heat-transference, it is practical in the improved spiral system of handling the steam to carry out the whole range of expansion from boiler-pressure to a moderate vacuum comprising several reductions in pressure and velocity, for which reason only one wheel for running 35 a turbine in opposite direction is shown.

The improved means of regulation permits one turbine to be used for handling loads varying from over-load to less than normal without decreasing the efficiency of the turbine; while for marine uses this means 40 overcomes the main objection hitherto had to turbines for propelling ships.

The before-described form of buckets used in connection with steam-chambers of gradually-increasing size, by which the expansion of the steam is utilized 45 to the fullest extent and nearly all the energy initially resident in the steam transformed into useful work, results when allowing for the inherent losses by mechanical friction, eddy currents, condensation and water mechanically entrained, in a steam-turbine of 50 the highest obtainable efficiency.

Having thus described my invention, I claim as new and desire to secure by Letters Patent:

1. A turbine-wheel provided with curved channels, and a division-wall protruding into the channels, forming buckets therewith, and relatively stationary to the moving turbine-wheel.

2. A turbine-wheel provided with double U-shaped channels, division-walls adapted to form buckets with each of the channels, so that each bucket has its inlet-end at one side of each division-wall belonging thereto, and its outlet-end at the other side of the same, the inlet-ends of the channels forming the double U-shaped channels being in proximity to each other.

3. A turbine wheel provided with double U-shaped channels, division-walls adapted to form buckets with each of the channels, and relatively stationary to the moving tur-

bine wheel, so that each bucket has its inlet-end at one side of each division-wall belonging thereto, and its outlet-end at the other side of the same.

4. A steam turbine, comprising a turbine wheel provided with double U-shaped channels, division-walls adapted to form buckets with the channels, so that each bucket has its inlet-end at one side of each division-wall and its outlet-end at the other side, and means to guide the steam in two spiral paths, each path meeting and joining the other, and then again separating preparatory to entering each of the channels of each double U-shaped channel.

5. A steam turbine, comprising a casing, a steam inlet for the same, a steam outlet for the same, a turbine wheel provided with a plurality of double U-shaped channels, division walls forming buckets with the channels, so that each bucket has its inlet end at one side of each division-wall, and its outlet end at the other side, the buckets so formed having their inlet end adjacent each other, a plurality of nozzles adapted to direct the steam into the buckets, and a plurality of partitions in said casing dividing the same into admission and twin release chambers, said partitions being so arranged as to cause the steam to partake of a spiral path from the steam inlet to the steam outlet in such a manner that the steam passes from the admission chambers into the nozzles, from the same into the inlet ends of the buckets in which the steam divides into two parts, each of which enters one of the twin release chambers, and from the same simultaneously enters the next admission chamber common to both inlet ends of the buckets, from which it again passes through the nozzles, buckets and twin release chambers.

6. A steam turbine, comprising a high pressure intermediate pressure, and a low pressure casing, steam inlets for the high pressure casing, steam outlets for the low pressure casing, a turbine wheel in each casing provided with channels, a division-wall forming buckets with the channels so that each bucket has its inlet end on one side of the division-wall and its outlet end at the other side, a plurality of partitions in each of said casings dividing the same into admission and release chambers for conducting the steam in a spiral path successively from one admission chamber through the buckets into a release chamber and then into the next admission chamber, and steam pipes connecting the high, intermediate, and low pressure casings.

7. In a steam-turbine, having a casing, and a turbine-wheel having buckets, a plurality of steam-inlets communicating with each other and with the casing, and adapted to vary the degree of expansion of the steam entering the buckets, all of said inlets directed against said turbine-wheel.

8. In a steam-turbine having a casing, and a turbine-wheel with buckets, a plurality of steam-inlets arranged adjacent each other and all directed against said turbine-wheel, valves in each steam-inlet adapted to cause the steam to pass through one or both of said steam-inlets so as to vary the degree of expansion of the steam entering the buckets.

9. A steam turbine, comprising a turbine wheel having buckets; a plurality of intercommunicating admission and release chambers, and a plurality of steam inlets arranged adjacent each other and in communication with the admission chambers; said steam inlets being adapted to vary the degree of expansion of the steam passing through the buckets, admission and release chambers.

10. A steam turbine, comprising a casing; a turbine wheel therein having buckets, a plurality of intercommunicating admission and release chambers, a plurality of steam inlet valves controlling the steam entering the casing, and a plurality of valves adapted to prevent the steam from passing from the chamber in which the inlet valve is open to the adjacent chamber.

11. A steam turbine, comprising a turbine wheel having buckets, a plurality of intercommunicating admission and release chambers gradually increasing in size, a plurality of steam inlets adjacent to each other, and above the admission and release chambers, valves for said steam inlets, each of said valves being adapted to regulate the passage of the steam passing from the steam inlet to the admission

chamber and to regulate the passage of the steam passing from the preceding release chamber to the aforesaid admission chamber.

12. A steam turbine, comprising a high pressure, intermediate pressure, and a low pressure casing, diaphragms between said casings, steam inlets for the high pressure casing, steam outlets for the low pressure casing, a turbine wheel in said casing provided with holes and with buckets and grooves at its circumference, a plurality of partitions in each casing dividing the steam into admission and release chambers for conducting the steam successively from one admission chamber through the buckets into a release chamber and then into the next admission chamber, and steam pipes connecting the high pressure, intermediate pressure and low pressure casings.

13. A steam turbine, comprising a casing, a plurality of partitions in said casing forming admission and release chambers, rings secured to said casing, admission blades supported by said rings, a second set of rings secured to said casing concentric to said first named rings, the adjacent walls of said two sets of rings being beveled, and a turbine wheel in said casing provided with buckets.

14. A steam turbine, comprising a casing, a plurality of partitions in said casing forming admission and twin release chambers, a plurality of nozzles in communication with said admission chambers, a plurality of channels in said casing, a division wall forming buckets with said channels, so that each bucket has its inlet end at one side of the division wall and its outlet end at the other side, the turbine wheel in said casing provided with a plurality of channels, a division wall forming buckets with said channels, so that each bucket has its inlet end at one side of the division wall, and its outlet end at the other side, said buckets being so arranged that the steam passing from the nozzles enters the buckets of the turbine wheel, passes from the same into the buckets of the casing, and from these buckets into another set of buckets of the turbine wheel, and from these into the twin release chambers.

15. A steam turbine, comprising a casing having a plurality of channels, a division wall forming buckets with the channels so that each bucket has its inlet end at one side of the division wall and its outlet end at the other side, and a turbine wheel in said casing having a plurality of channels, a division wall forming buckets with the channels so that each bucket has its inlet end at one side of the division wall and its outlet end at the other side, the buckets of the turbine wheel being arranged in series so that the inlet end of each bucket is adjacent the outlet end of the preceding bucket, the inlet ends of the first of each series of buckets being adjacent each other, the buckets of the casing and wheel being so arranged that the outlet ends of the wheel buckets communicate with the inlet

ends of the casing buckets and the outlet ends of the casing buckets with the inlet ends of the next series of wheel buckets.

16. A steam turbine, comprising a casing having a plurality of U-shaped channels, division walls forming buckets with the channels so that each bucket has its inlet end at one side of each division wall and its outlet end at the other side, and a turbine wheel in said casing having a plurality of U-shaped channels, division-walls forming buckets with the channels, so that each bucket has its inlet end at one side of each division wall, and its outlet end at the other side, the buckets of the casing and of the turbine wheel being so arranged that the outlet ends of the wheel buckets communicate with the inlet ends of the casing buckets and the outlet ends of the casing buckets with the inlet ends of the next series of wheel buckets.

17. A steam turbine, comprising a casing having a plurality of U-shaped channels, division-walls forming buckets with the channels, so that each bucket has its inlet end at one side of each division-wall and its outlet end at the other side, and a turbine wheel in said casing having a plurality of U-shaped channels, division-walls forming buckets with the channels, so that each bucket has its inlet end at one side of each division-wall and its outlet end at the other side, the wheel buckets being arranged in series so that the inlet end of each bucket is adjacent the outlet end of the preceding bucket, the inlet ends of the first of each series of buckets being adjacent each other, the buckets of the casing and the wheel being so arranged that the outlet ends of the wheel buckets communicate with the inlet ends of the casing buckets, and the outlet ends of the casing buckets with the inlet ends of the next series of wheel buckets.

18. A steam-turbine, comprising a high-pressure casing, an intermediate-pressure casing, a low-pressure casing, means connecting the high-pressure casing with a steam supply, means connecting the high-pressure casing with the intermediate-pressure casing, means connecting the last named casing with the low-pressure casing, a plurality of intercommunicating admission and release chambers in each of said casings, a turbine-wheel in each casing, an additional reversing turbine-wheel in the low-pressure casing, a plurality of intercommunicating admission and release chambers for said reversing turbine-wheel, and means supplying the reversing turbine-wheel with steam.

In testimony, that I claim the foregoing as my invention, I have signed my name in presence of two subscribing witnesses.

JOHN W. SMITH.
